UNITED STATES PATENT OFFICE

ERNST RICHARD MEINIG, OF WYOMISSING, PENNSYLVANIA, ASSIGNOR TO E. RICHARD MEINIG CO., INC., OF READING, PENNSYLVANIA, A CORPORATION OF PENNSYLVANIA

DYEING PROCESS AND APPARATUS

Application filed March 14, 1929. Serial No. 348,958.

This invention relates to improvements in dyeing, and more especially to a novel process and apparatus for use in dyeing hosiery or the like.

5 Heretofore, in dyeing hosiery, it has been the general practice to place the articles in a tumbling drum containing the dyeing liquid, and to then rotate or oscillate the container. This results in rubbing of the articles against 10 one another, so that frayed places are formed, and as the dye may not uniformly reach all parts of the mass of stockings or the like, there may be variations in the shades of the color of the finished hosiery. Consequently, a 15 number of the articles may be so unfavorably affected as to necessitate the discarding of the same, or their sale as "seconds".

Some effort has been made to eliminate these disadvantages by neatly arranging the 20 stockings in superposed relation, during the dyeing, but even this expedient has not solved the problem.

I have discovered that these drawbacks may be obviated by subjecting the fabrics to the 25 dye bath while longitudinally stretched as upon suitable forms. I have also discovered that the dyeing process is improved if the stockings, while thus longitudinally stretched upon the forms, are maintained substantially 30 out of contact with one another during the immersion, as this prevents any rubbing of one garment against another, which might result in fraying of the threads. I have also found that the process is enhanced if the dyeing 35 is practiced while the articles are longitudinally but not laterally stretched upon forms which do not conform to the configuration of the stockings. If the stockings, during the dyeing, are stretched upon flat forms 40 having a leg-outline at the lines of contact between the stocking and the lateral edges of the form, noticeable lines will appear on the dyed stockings; and in order to eliminate this I stretch the stockings longitudinally 45 during the dyeing, on forms which are relatively narrow in comparison with the hose enclosing upon the same.

From the foregoing, it will be seen that one 50 of the main objects of the invention is to provide an improved process of fabric dyeing,

which consists in supporting a series of fabrics in longitudinally tauted non-contacting relation, and subjecting the fabrics while so supported, to immersion in a vat of dyeing liquid.

Another object is to practice such a process while moving the fabrics in the dyeing liquid, for agitating the latter, and such movement is preferably in an endless path.

Another object is to furnish a novel apparatus designed to support a series of fabrics in longitudinally tauted, non-contacting relation, and to dip said fabrics in a dye vat, and to move the fabrics in endless paths while they are immersed in the dyeing liquid.

With the foregoing objects outlined and with other objects in view which will appear as the description proceeds, my invention consists in the novel features hereinafter described in detail, illustrated in the accompanying drawings, and more particularly pointed out in the appended claims.

Referring to the drawings,

Fig. 1 is a transverse vertical sectional view of a portion of a dyeing vat containing dyeing liquid, and showing my improved apparatus cooperating therewith.

Fig. 2 is a longitudinal vertical sectional view of the same, taken on the line 2-2 of Fig. 1.

Fig. 3 is a top plan view of the apparatus.

Referring to the drawings, 10 indicates a dyeing vat containing a pool of dyeing liquid 11. This vat may be of any preferred construction, and of course, the dyeing liquid 15 may be of any desired color or character.

My improved mechanism preferably includes an upstanding cylinder 12 containing a ram or plunger 13 which may be raised or lowered by properly controlling a pressure fluid travelling through the conduit 14. Arranged at the top of the ram, and supported thereby, is a head 15 which carries a number of rotatable shafts 16, that may be driven in unison by means of meshing gears 17 fixed 20 on the shafts 16. One of the shafts supports a worm gear 18 that is fast on that shaft, and when the ram is in lowered position, the worm gear may be driven by a similar gear 19, that is fast on the driving shaft 20. 25

Thus, while the head 15 is in lowered position, the gears 17 may be simultaneously rotated, but when the ram is elevated, the worm 18 will disconnect itself from the gear 19, 5 due to the fact that the shaft 20 is supported in stationary bearings 21, carried by a bracket 22 which is mounted in a stationary manner on the cylinder 12. Some of the shafts 16 project through the 10 front wall of the head 15, and arms 23 are fast on the projecting ends of these shafts. Each arm carries anti-friction bearings 24 in which a stub shaft 25 is journaled. One pair of the stub shafts 25 are fixed to upwardly projecting ears 26 on a bracket 27, 15 and the other pair of stub shafts are similarly fixed to ears 28 that extend upwardly from a bracket 29. As one pair of the arms 23 normally extend in one direction, and the 20 other pair normally extends in the opposite direction, it will be noted that one of the brackets 27, 29 will be in raised position, while the other is in lowered position, and vice versa. 25 Each of these brackets carries a series of rods 30; the rods of each series being spaced apart, and each rod being adapted to support a multiplicity of stocking forms 31, which have rings or eyes 32 at their upper 30 ends, to permit the rod 30 to be threaded through the same. Each of these forms is of special construction, claimed in Patent No. 1,761,402, issued to me June 3, 1930. For the purposes of the present disclosure, it 35 may be said that each form is flat and preferably made of wire, and includes parallel sides 33, which have converging extensions 34 that terminate in a point 35 that is adapted to engage the inner surface of the toe 40 of the stocking, when a stocking is fitted on the form. A T-shaped projection 36 is provided near the upper end of the form, and is adapted to be inserted into the usual slit of the welt portion at the top of the stocking. 45 Of course, these forms may be of various lengths to cooperate with stockings of different sizes, and as the form is relatively narrow and does not conform to the outline of the stocking when the latter is in flattened 50 condition, it will be understood that practically the only portion of the stocking which will contact with the form, even though the stocking encloses the greater portion of the form, will be the toe and welt; the flattened 55 walls of the laterally unstretched tubular stocking being free to sway more or less toward and from one another under action of the liquid surging therethrough, insuring uniform dyeing action. From Fig. 2 it will 60 be observed that the opposite sides of the ring of each form 31 are distorted for the purpose of spacing the forms apart without arranging any special spacing devices on the rods 30, and consequently, when a series of 65 the forms with stockings thereon, are sus-

pended on any one of the rods 30, the adjacent stockings will be supported in substantially non-contacting relation, so that the stockings will not rub against one another while they are dipped and moved in endless paths in the dyeing liquid 11. 70

It may be noted at this point, and as shown in Fig. 1, that the cylinder 12 has oppositely extending arms 37 which support guiding sleeves 38 for guide rods 39. These rods 75 are secured at their upper ends to the head 15, and they tend to guide and steady the head and the parts which the head carries, while these elements are being raised or lowered. 80

In operation, let us assume that the ram 13 is raised to the top of its path of movement. At such time, the rods 30 will be at proper elevations to support the forms 31 entirely above the vat 10, and at such time, the forms with the stockings thereon, will be threaded on to the rods 30, until each rod supports its quota of the forms. Now, the ram 13 will be lowered, and as the rods 30 are positioned above the vat 10, it will be 90 understood that the forms 31 will force the stockings which they carry, to be submerged in the dyeing liquid 11. When the stockings are immersed, the worm 18 will have come into engagement with the gear 19, and at 95 this time, the shaft 20 is set in motion to cause the gears 17 to rotate. As the arms 23 are mounted fixedly on certain of these shafts, it will be understood that each of the supporting brackets 27, 29 will now be moved 100 in an endless path, and as one of the brackets moves upwardly, the other will move downwardly, and vice versa. Consequently, the stockings carried by the brackets will also be moved in endless paths, through the dyeing liquid, and this will not only cause the liquid to be agitated, but each portion of the stocking will be uniformly brought into contact with the dyeing liquid. Of course, during this movement, while the flattened walls 110 may move toward and from one another, there will be no rubbing of the surfaces of the fabrics against one another, and consequently, the stockings will not be damaged 115 during the dyeing operation. 120

Furthermore, as all of the stockings will be subjected to the same amount of dipping, submersion and agitation, it will be apparent that all of the stockings will be uniformly dyed. 125

After the dyeing operation is completed, the operator will cause pressure fluid to flow through the pressure conduit 14, and thus elevate the ram 13. As the ram rises, the worm 18 will disengage the gear 19, so that movement of the brackets 27, 29 will be stopped, and when the head 15 has reached its highest position, the rings 32 of the stocking forms may be slid off the rods 30, and then the machine will be in position to receive another 130

lot of the stockings for the next dyeing operation.

While I have disclosed what I now consider the preferred embodiment of my invention, and explained the same for use in dyeing stockings, it is manifest that the machine and the process may be used for dyeing fabrics and various articles, and I do not wish to limit the invention to use in dyeing stockings alone.

From the foregoing it is believed that the construction, and operation of the machine, and the steps of the process may be readily understood, and I am aware that various changes may be made in the features disclosed, without departing from the spirit of the invention, as expressed in the claims.

What I claim and desire to secure by Letters Patent is:

1. A machine for use in subjecting fabrics to liquid treatment, comprising a vat adapted to contain a pool of the treating liquid, a vertically reciprocating plunger, a head carried by the plunger, a bracket supported by the head, means for moving said bracket in an endless path, rods carried by the bracket, and a series of forms supported by the rod in freely depending non-contacting parallel relation and adapted to be jointly raised from, and lowered into the vat by movement of said plunger.

2. In a machine of the character described, a vat adapted to contain a treating liquid, a bracket, means for raising and lowering the bracket, rods carried by the bracket, and fabric forms supported by the rods and extending into the vat, and means for maintaining the portions of the forms which extend into the vat, out of contact with one another.

3. In an apparatus of the character described, a vat adapted to contain a treating liquid, rotatable arms, a bracket having stud shafts rotatably mounted in the arms, a series of rods carried by the bracket and extending over the vat, forms suspended from the rods and extending into the vat, and means for maintaining the major portions of the forms out of contacting relation.

4. In an apparatus of the character described, a vat adapted to contain dyeing liquid, an upstanding cylinder arranged in close proximity to the vat, a vertically movable ram in the cylinder, a head supported by the ram, rotatable shafts carried by the head, means for rotating the shafts, arms fixed on certain of said shafts, certain of the arms extending in one direction and the other arms extending in the opposite direction, brackets having stud shafts loosely mounted in said arms, a series of rods carried by each bracket and extending over the vat, and fabric forms suspended from the rods and extending into the vat.

5. The improved process of hosiery dyeing, which consists in suspending a depend-

ing series of separately supported longitudinally stretched loosely flattened stockings, and subjecting said series of normally spaced longitudinally stretched stockings to immersion in a pool of dyeings liquid and permitting the side walls of each stocking to move toward or away from each other.

6. The improved process of fabric dyeing which consists in longitudinally stretching tubular fabrics on individual laterally loosely fitting supports, mounting a series of said supports in a fixedly spaced depending relation, and subjecting said series to immersion in a pool of dyeing liquid.

7. The improved process of fabric dyeing which consists in longitudinally stretching tubular fabrics on individual flat loosely fitting supports, mounting a series of said supports in depending fixedly spaced flat relation, and subjecting said series to immersion and edgewise agitation in a pool of dyeing liquid.

In testimony whereof I affix my signature.

ERNST RICHARD MEINIG.
